US00D824877S

(12) **United States Design Patent** (10) Patent No.: **US D824,877 S**
Kim et al. (45) Date of Patent: ** Aug. 7, 2018

(54) **BLUETOOTH HEADSET**5/0335; H04R 1/1033; H04R 1/105;
H04R 1/1083(71) Applicant: **LG ELECTRONICS INC.**, Seoul
(KR)

See application file for complete search history.

(72) Inventors: **Dongsoon Kim**, Seoul (KR); **Seungyup Lee**, Seoul (KR); **Chanwoo Park**, Seoul (KR)(73) Assignee: **LG ELECTRONICS INC.**, Seoul
(KR)(**) Term: **15 Years**(21) Appl. No.: **35/503,036**(22) Filed: **Nov. 23, 2016**(80) **Hague Agreement Data**Int. Filing Date: **Nov. 23, 2016**Int. Reg. No.: **DM/094130**Int. Reg. Date: **Nov. 23, 2016**Int. Reg. Pub. Date: **May 26, 2017**(30) **Foreign Application Priority Data**

May 26, 2016 (KR) 30-2016-0025503
